(57) **CLAIM**

The ornamental design for a shellfish cracking device, as shown and described.

DESCRIPTION

FIG. 1 is a perspective view of the shellfish cracking utensil according to the design.

FIG. 2 is a view of one end of the shellfish cracking utensil according to the design.

FIG. 3 is a view of the opposite end of the shellfish cracking utensil according to the design.

FIG. 4 is a side view of the shellfish cracking utensil according to the design.

FIG. 5 is a top view of the shellfish cracking utensil according to the design; and,

FIG. 6 is a bottom view of the shellfish cracking utensil according to the design.
